TOY PUMP GUN

**Charles F. Lefever, Plymouth, Mich., assignor to
Daisy Manufacturing Company, Plymouth,
Mich., a corporation of Michigan**

Application April 16, 1945, Serial No. 588,431

4 Claims. (Cl. 124—13)

1

The invention relates to toy guns and has for its object the obtaining of a construction of pop gun which simulates a real gun and can be manufactured at relatively low cost.

It is the object of the instant invention to obtain a construction of toy gun which while using some metal parts is, nevertheless, largely formed of wood, thereby reducing on the cost of manufacture. To this end the invention consists in the construction as hereinafter set forth.

In the drawings:

Fig. 1 is a side elevation of my improved gun;

Fig. 2 is a longitudinal section through a portion of the telescopically engaged barrel sections;

Fig. 3 is a similar view through the forward barrel section;

Fig. 4 is a cross section on line 4—4, Fig. 2.

A and B are two telescopically engaged tube members which form the barrel of the gun. C is a stock section preferably formed of wood and secured to the rear tube section B. D is a pump handle section also preferably formed of wood and connected to the forward tube portion A. Within the forward tube section A and extending rearward into the telescopically engaged portions of the tubes A and B is a rod E preferably formed of wood and having at its forward end a cup-shaped packing member F secured thereto by a screw G. The member F fits within the tube A forming a piston therefor, the tube constituting an air cylinder. The forward end of the tube A is slightly flared as at A' to receive a cork or stopper H. This is attached to the rod E by a cord connection I which passes through the stopper H and is secured by a washer J adjacent to the head of the screw G. Both tubes A and B are secured to the stock member C by a screw K, which passes through apertures in the tube B and slots A² in the tube A; also, through the rear end of the rod E and into the stock C. The tube B is further secured by a nail L which passes therethrough and into the stock C near the rear end of said tube. The slots A² in the tube A permit of moving the tube A telescopically within the tube B for a distance equal to the length of said slots. The rod E is, however, held stationary and, as this rod is connected by the cord I with the stopper H, a forward movement of the tube A will draw said stopper into sealing engagement with the flared forward end A' of said tube. With the construction as described the gun is cocked by moving the tube or barrel section A forward by means of the pump handle D secured thereto. This, as above described,

2

will draw the stopper H into sealing engagement with the forward end of the barrel. To fire the gun the pump handle D is quickly drawn rearward, which by movement of the barrel A will compress air between the packing F and stopper so that when sufficient pressure is attained, the stopper will be expelled with a loud report. Rearward movement of the handle D is limited by a pin M projecting from the end thereof, which holds this end spaced from the stock C and avoids danger of pinching the hand of the operator. The construction as above described has comparatively few parts which are easily assembled with each other so that the cost of manufacture is relatively low.

What I claim as my invention is:

1. A toy gun comprising telescopically engaged tube sections together forming a barrel having the outer tube extending rearwardly of the inner tube, a rod within the inner tube extending toward the muzzle and having a packing at its forward end constituting an air expelling piston within the barrel, a stopper for the forward end of the barrel, a flexible connection between said stopper and rod, a stock connected to the rear portion of the outer member of said telescopically engaged tubes and a screw passing through aligned apertures in the outer tube, through slots in the inner tube terminating forward of its rear end, through said rod and into said stock, said screw forming a means securing the barrel to the stock, an anchor for said rod, and a limit for the forward telescopic movement of the forward tube.
2. A toy gun comprising telescopically engaged tube sections together forming a barrel, a rod within the inner tube extending toward the muzzle and having a packing at its forward end constituting an air expelling piston within the barrel, a stopper for the forward end of the barrel, a flexible connection between said stopper and rod, a stock, a screw passing through aligned apertures in the outer tube, through slots in the inner tube terminating forward of its rear end, through said rod and into said stock, said screw forming a means securing the barrel to the stock, an anchor for said rod and a limit for the forward telescopic movement of the forward tube, and an additional securing pin passing through the rear portion of the outer tube beyond the end of the inner tube and engaging said stock.
3. A toy gun comprising telescopically engaged tube sections together forming a barrel, a rod within the inner tube extending toward the

muzzle and having a packing at its forward end constituting an air expelling piston within the barrel, a stopper for the forward end of the barrel, a flexible connection between said stopper and rod, a stock, a screw passing through aligned apertures in the outer tube, through slots in the inner tube terminating forward of its rear end, through said rod and into said stock, said screw forming a means securing the barrel to the stock, an anchor for said rod and a limit for the forward telescopic movement of the forward tube, an additional securing pin passing through the rear portion of the outer tube beyond the end of the inner tube and engaging said stock, and a pump handle secured to the forward tube limiting the rearward movement thereof by means of a rearwardly projecting pin for abutting against the stock.

4. A toy gun comprising telescopically engaged tube sections together forming a barrel having the outer tube extending rearwardly of the inner tube, a rod within the inner tube extending toward the muzzle and having a packing at its

5
10

forward end constituting an air expelling piston within the barrel, a stock connected to the rear portion of the outer member of said telescopically engaged tubes and a screw passing through aligned apertures in the outer tube, through slots in the inner tube terminating forward of its rear end, through said rod and into said stock, said screw forming a means securing the barrel to the stock, an anchor for said rod, and a limit for the forward telescopic movement of the forward tube.
